UNITED STATES PATENT OFFICE

96,192

DESIGN FOR A TOILET ACCESSORY CONTAINER

Joseph S. Lindemann, New York, N. Y., assignor to Maison Joubert, Inc., New York, N. Y., a corporation of New York

Application April 18, 1935, Serial No. 56,448

Term of patent 14 years

To all whom it may concern:

Be it known that I, Joseph S. Lindemann, a citizen of the United States of America, residing at New York city, county of New York, Borough of Manhattan, and State of New York, have invented a new, original, and ornamental Design for a Toilet Accessory Container, of which the following is a specification, reference being had to the accompanying drawing, forming a part thereof.

I claim:—

The ornamental design for a toilet accessory container as shown.

JOSEPH S. LINDEMANN.
